UNITED STATES PATENT OFFICE.

OTTO PATSCHECK, OF HESPERUS, COLORADO.

WIRE-REEL CARRIER.

1,175,289.

Specification of Letters Patent. Patented Mar. 14, 1916.

Application filed June 5, 1915. Serial No. 32,400.

To all whom it may concern:

Be it known that I, OTTO PATSCHECK, a citizen of the United States, residing at Hesperus, in the county of La Plata and State of Colorado, have invented certain new and useful Improvements in Wire-Reel Carriers, of which the following is a specification, reference being had to the accompanying drawings.

10 This invention relates to improvements in reel carriers for unreeling and stretching fence wires or for analogous purposes and the primary object of the present invention is the provision of a very simple reel carrier adapted to be drawn over the ground and having the form of a sled and provided with a reel or reels supported upon the carrier in such position that certain portions of one of the reels will engage with the ground to assist in unreeling the wire and also particularly to retard the unreeling of the wire from the reels.

15 A further object of the invention is the provision of a wire reel carrier of the character above described wherein a plurality of reels are used disposed in different planes, means being provided for retarding the unreeling of the wire from one of the reels for the purpose above stated.

20 30 Other objects will appear in the course of the following description.

My invention is illustrated in the accompanying drawings wherein—

Figure 1 is a plan view of my wire unreeling carriage, the rear end of one of the runners being broken away; Fig. 2 is a vertical sectional view of Fig. 1; Fig. 3 is a plan view of Fig. 1 with the upper reel removed and with the braces 16 removed; and Fig. 4 is a transverse section showing a different manner of actuating the horizontally disposed reel.

40 Referring to these drawings, 2 designates a sledge or like carriage which is provided with the oppositely disposed parallel runners 3, the transverse braces 4, 5 and 6, and the cross braces 7 which extend beneath the brace 5 and intersect at the middle of the brace. Extending through the rear ends of the runners is a shaft 8 which may have the form of an elongated bolt provided with a head 9 at one end and a nut or other fastening device at the other end. This shaft is preferably provided at its head 9 with a square portion which engages the square socket in a runner and thus prevents rotation of the shaft.

50 Mounted upon this shaft to rotate thereon is the spool or reel 10. This spool has end flanges 11 and the diameter of these flanges is such that the distance between the center of the shaft 8 and the peripheries of the flanges is greater than the distance between the center of said shaft and the lower surfaces or edges of the runners 3, whereby when the runners 3 are directed along the ground, the peripheries of the flanges will engage the ground and rotate thereon in the manner of a wagon wheel.

55 Passing vertically through the intersecting portions of the braces 7 and 5 is a shaft 12 carrying upon it the two pairs of cross bars 13. These bars are preferably notched into each other so as to be firmly held in right angular position and the ends of the bars are engaged by transversely extending pins 14 having preferably the form of bolts with spacing members 15 surrounding the bolts. Nuts 15^a engage the ends of these arms and hold the arms in proper relation upon the spacing members. The upper end 60 of the shaft 12 is supported by means of braces 16 which are pivotally secured to the forward ends of the runners 3 and extend upward and over the upper end of the shaft. By detaching these braces the shaft 65 may be removed together with the reel, but normally the braces hold the shaft in position upon the reel and prevent any upward movement thereof. The reel formed by the members 13 and the pins 14 is preferably fast upon the shaft so as to rotate therewith and this shaft extends downward below the braces 7 and is supported in a cross brace. Links or shackles 17 are pivotally connected to the forward ends of the 70 runners and to these shackles the draft chains are applied. The runners are preferably shod as at 18, but I do not wish to be limited to any of the details of construction of the sledge itself.

75 100 In the practical use of my device, the sledge is drawn over the ground and the wire unreeled from the spool or reel 10 and the reel formed by the members 13. It will, of course, be understood that separate wires are unreeled from the spool 10 and from the reel 13, that is, two distinct kinds of wire. The spool or reel 10 is designed for use in unreeling barb wire which, as is known, is ordinarily sold in spools and in 105 unreeling this barb wire, the operator simply fastens the end of the wire to a post

- or other support at the starting point from where it is desired to unreel the wire. By fastening the end of the barb wire and drawing the sledge along the ground, the 5 wire is kept straight and in its proper place as it is unreeled and the engagement of the peripheries of the flanges 11 with the ground will properly retard the unreeling of the wire and avoid any slack.
- 10 The reel 13 is designed for use in connection with wire that is known as spring coil wire which comes in coils like rope. This wire is laid flat-wise on the reel 13, that is, between the two pairs of cross bars 15 and the end of it is tied to a post or starting place and as the carriage or sledge is drawn over the ground, the wire will unreel and be kept straight and in proper place. Preferably, when the reel 10 is used, 20 the reel 13 is unshipped or taken off, the device then being as illustrated in Fig. 3 of the drawing.

It is obvious that as shown in Fig. 4 the shaft 12 may carry a beveled gear wheel 19 25 in turn engaged with a beveled gear wheel 20 mounted upon a shaft 21, this shaft carrying rollers engaging the ground. Thus in this case the shaft 12 will be rotated at a predetermined speed to unreel the wire and 30 undue unreeling will be prevented.

Having described my invention what I claim is:

1. A wire reel carrier of the character described, comprising a carriage embodying sled runners adapted to be drawn along the 35 ground, a shaft carried by said runners

and extending across the same from one to the other, and a reel mounted on said shaft and provided with flanges, the distance between the center of the shaft and the peripheries of said flanges being greater than the distance between the center of the shaft and the lower faces of the runners, whereby as the carriage is drawn along the ground, the peripheries of the flanges of the reel will 45 engage with the ground, as and for the purpose set forth.

2. A wire reel carrier of the character described, comprising a carriage embodying sled runners adapted to be drawn along the ground, a horizontally disposed reel carried by said runners and revoluble about a vertical axis thereon, a shaft carried by said runners in the rear of said reel and extending across the runners from one to the other, and a second reel mounted on said shaft and provided with flanges, the distance between the center of the shaft and the peripheries of said flanges being greater than the distance between the center of the 50 shaft and the lower faces of the runners, whereby as the carriage is drawn along the ground, the peripheries of the flanges of the second named reel will engage with the ground, as and for the purpose set forth. 55

In testimony whereof I hereunto affix my signature in the presence of two witnesses.

OTTO PATSCHECK.

Witnesses:

J. L. McNEIL,
GEORGE H. FITZ.
